HENRY J. SCHAFER, OF BROOKLYN, NEW YORK, ASSIGNOR TO JACOB SCHAFER,
OF BROOKLYN, NEW YORK.

CONTAINER.

Application filed January 14, 1925. Serial No. 2,264.

- This invention relates to containers of sheet metal, and has for an object to provide an improved container with a removable cover, either the cover or the casing of which may be 5 lifted without the use of outwardly projecting handles; which will permit of ventilation of the container through the walls; and which will at the same time prevent the entrance into the container of mice and bugs.
- 10 A further object is to provide an improved container for accomplishing each and all of the above objects which will be simple in construction, convenient, and relatively inexpensive.
- 15 Various other objects and advantages will be apparent from the following description of an embodiment of the invention and the novel features will be particularly pointed out hereinafter in the appended claims.
- 20 In the accompanying drawing:

Fig. 1 is an end elevation of a sheet metal clothes hamper, constructed in accordance with the invention;

Fig. 2 is a plan of the same; and

Fig. 3 is a section through the handle portion of either the end walls or cover, the particular section illustrated being taken substantially along the line 3—3 of Fig. 2.

In the illustrated embodiment of the invention, the container comprises a sheet metal casing 1 which is rectangular in cross section and relatively deep to serve as a clothes hamper, and is also provided with a removable cover 2 of sheet metal. The two opposite 35 end walls of the casing are each provided near the top with a pair of horizontally arranged apertures 3, spaced a distance apart convenient for the insertion of one's fingers, when lifting the container. The cover 2 is also 40 provided in its interior, preferably the central portion, with a pair of spaced apertures 4, similar to the apertures 3, and spaced apart an amount permitting the ready insertion of a thumb and one of the other fingers of one's 45 hand when lifting the cover.

Referring particularly to Fig. 3 where a section through apertures in either case, is illustrated, the sheet metal wall immediately surrounding and defining the aperture is 50 struck or pressed outwardly as at 5, and then rolled inwardly and backwardly as at 6, to provide a tubular bead defining the aperture, so that no sharp edges, which would cut one's 55 fingers, will define the apertures. Therefore, there will be no danger of cutting one's fin-

gers in lifting the casing or cover with the fingers hooked around a wall of the aperture. In order to permit of the rolling of the bead inwardly and backwardly, the extreme inner open edge of the rolled metal may be slotted 60 radially for a short distance from the free edge which is rolled back, and these slits will not show in the exterior of the apertured wall.

The bead 5 stiffens the wall at the aperture, so as to prevent distortion of the sheet metal 65 surrounding the aperture when the lifting forces are applied thereto. The bead will also provide a blunt surface for engagement by the fingers, so that it will not cut or indent into the flesh of the fingers, when the cover 70 or casing is being lifted. The apertures are of greater diameter than the diameter of a thumb or finger of one's hand, so that the latter may be readily passed through said apertures and hooked under the walls of said apertures to apply lifting forces thereto.

These apertures will provide ventilation for the container, but since they are large enough to permit of the ready insertion of one's fingers, they will also permit the entrance into the container of bugs and mice, which is particularly objectionable. Accordingly, I prefer to provide a sheet metal protecting means across the apertures on the inner face of the apertured wall, spaced from 80 the wall sufficiently to permit of the insertion of the tip ends of one's fingers through the apertures, and leaving an exposed margin around the apertures on the inner face of the walls sufficient to permit of hooking of the 85 finger tips under said exposed margin when lifting forces are applied.

While one large sheet metal cup might be placed over all of the apertures of a group forming a handle, I prefer to employ individual cups or shells 7 formed of sheet metal, each having an outwardly peripheral flange 8 at the open edge, which flanges 8 fit against the inner faces of the apertured walls. The 90 cups are secured to the walls in any suitable 95 manner, such as by soldering, and are of greater diameter than the apertures 3 which they cover, so that when applied to the apertured wall approximately concentric with an aperture they will leave exposed a marginal 100 strip on the inner face of the wall immediately bordering the aperture. Thus the portion of the wall defining the aperture will project 105 slightly over the open face of the cup.

The cups are preferably each provided with 110

a plurality of small apertures 9 which will permit of ventilation of the container through the apertures 3, but which, at the same time, are sufficiently small to prevent the entrance into the container of bugs or mice. By making separate cups for each aperture, I am able to utilize scrap sheet metal for the material of the cups, thus considerably reducing the cost.

10 It will be observed that with this construction, the container does not have any outwardly projecting straps or handles by which the casing or cover may be lifted, and at the same time, the casing or cover may be 15 lifted by inserting the fingers through the apertures of either the casing or cover and lifting. The apertured cups prevent the entrance into the container of mice or bugs, while at the same time permitting ventilation 20 of the container through said apertures. Such a construction is exceptionally simple and inexpensive, and very satisfactory in use.

25 It will be obvious that various changes in the details, which have been herein described and illustrated for the purpose of explaining the nature of the invention, may be made by those skilled in the art within the principle and scope of the invention, as expressed in the appended claims.

30 I claim:

1. A container, having sheet metal walls with spaced apertures therein, said apertures each being larger in diameter than the diameter of any of a person's fingers, with the 35 spacing between the apertures such as to permit of the insertion into the apertures of the fingers of one's hand to enable one to lift the apertured wall, the portion of the wall bordering each aperture being raised upwardly 40 slightly and rolled inwardly and backwardly to provide a bead defining each aperture, and individual sheet metal cups, each of greater diameter than the diameter of any 45 of a person's fingers, flanged at their open edges and secured against the inner face of the apertured wall over an aperture.

2. A container, having sheet metal walls provided with spaced ventilating apertures through which the fingers of a person's hand 50 may be inserted for lifting the apertured wall, and sheet metal cups of greater diameter than the apertures, flanged at their open edges and secured by soldering the flanges against the inner face of the apertured 55 wall over the apertures, so as to permit of the insertion of fingers through the apertures for lifting purposes, said cup being of such size as to protect the contents of said container against the finger and simultaneously providing ventilation therefor while preventing the entrance into the container of mice and bugs.

60 3. A container, having sheet metal walls provided with spaced apertures through 65 which the fingers of a person's hand may be

inserted for lifting the apertured wall, said apertures having a beaded edge integral with the metal wall of said container, extending in a rounded curve beyond both sides thereof, and sheet metal cups of greater diameter 70 than the apertures, having outwardly extending flanges at their open edges and permanently secured by the flanges against the inner face of the apertured wall over the apertures, so as to permit of the insertion of one's fingers through the apertures for lifting purposes while preventing the entrance into the container of mice and bugs, said cups being provided with a plurality of small apertures to permit of ventilation of the container through said apertures. 75

4. A container having a sheet metal wall provided with a lifting hole of a size freely to receive a single finger, a rounded finger-protecting bead surrounding and defining said hole, and a finger-receiving cover-cup member at the inner side of said wall having its open end surrounding said hole and secured to said wall and of sufficiently larger 80 transverse area than said hole to provide a firm grip of the bent finger around and inward from said bead within the cup member. 85

5. A container having a sheet metal wall provided with a circular lifting hole of a diameter freely to receive a single finger, a rounded finger-protecting bead surrounding and defining said hole, and a circular finger-receiving cover-cup at the inner side of said wall having its open end surrounding said hole concentric therewith and secured to said wall and of sufficiently larger diameter than said hole to provide freedom of movement of the finger therein and providing within the cup an inner annular margin on said wall of sufficient width to provide a firm grip of the bent finger around said bead and upon said inner annular margin of the wall. 95

6. A container having a sheet metal wall provided with a circular lifting hole of a diameter freely to receive a single finger, a hollow rounded finger-protecting bead surrounding and defining said hole and formed by turning inward a marginal portion of the wall to lie at its edge against the inner side of the wall, and a circular sheet metal finger-receiving cover-cup at the inner side of said wall having its open end concentrically surrounding said hole and provided with an outwardly extending flange lying against the inner face of and secured to said wall and said cup being of larger internal diameter than said hole to provide an inner annular marginal portion on said wall surrounding said hole within the cup of sufficient width to give free finger movement within said cup and to provide a firm grip of the finger around said bead and against said inner annular wall portion. 100

7. The invention defined in claim 4, in which the said finger-receiving cover-cup is 105 110 115 120 125 130

provided with a plurality of small apertures forming a screen for ventilating the container while permitting the free insertion of the end of the finger into the cup and protecting the contents of the container from contact with the finger.

8. The invention defined in claim 6, in which said finger-receiving cup has an enclosing cylindrical side wall and a perforated inner screen-forming end wall formed in one piece with its side wall at the inner end thereof.

9. The combination of a pair of the finger-receiving lifting devices as defined in claim

4, said devices being suitably spaced and arranged for the concomitant insertion therein respectively of two of the fingers of the same hand.

10. The invention defined in claim 6, further comprising the combination of two of the said lifting devices defined therein to form a pair of such devices suitably spaced and arranged for the concomitant insertion into each of said devices of a different finger on the same hand.

In witness whereof, I hereunto subscribe my signature.

HENRY J. SCHAFFER.
